AKTIEBOLAGET LIDKÖPINGS MEKANISKA VERKSTAD, OF LIDKÖPING, SWEDEN, A
CORPORATION.

LATHE-BED.

1,389,687.

Specification of Letters Patent.

Patented Sept. 6, 1921.

Application filed September 22, 1919. Serial No. 325,422.

To all whom it may concern:

Be it known that we, KARL OLSSON and ANDERS HILMER OLSSON, both subjects of the King of Sweden, residing at Lidköping, 5 Sweden, have invented a new and useful Lathe-Bed, of which the following is a specification.

In lathe beds with front and back slides the latter are often provided with longitudinal gibs, preferably of V-shaped cross section, to guide the saddle or carriage.

The slots of the saddle fitting these gibs reduce the strength of the saddle to a considerable extent, this being particularly the 15 case with the front slot in which the saddle is subjected to the most severe strain due to the pressure of the tool. Thus, the greatest strength possible should be provided at this place.

20 To attain this, the front slide of the lathe bed is lowered relatively to the back slide in such manner that the upper edge of the gib of the front slide is situated at the same level or lower than the back slide, or at any 25 rate lower than the upper edge of the gib of the back slide. By this arrangement evidently a considerable increase of the bulk of the saddle or the support and a corresponding increase in the strength thereof is attained.

The accompanying drawing illustrates by way of example a lathe bed constructed according to the invention, the same being shown in cross section.

35 1 and 2 denote the front and the back slides respectively, the same being provided

with the guiding gibs 3 and 4 respectively. The front gib 3 is situated according to the invention with its upper edge at a level with the back slide 2, that is to say the front slide 40 1 is lowered so much below the back slide 2 as corresponds to the height of the gib 3, and thus a corresponding increase in the thickness of the material, counted in a vertical direction, is obtained at the fore edge 45 of the saddle or the carriage. Consequently, the saddle becomes rigid enough to take up even the greatest tool pressure without vibrating.

The saddle or carriage rests on the back 50 slide 2 and the front gib 3, while the back gib 4 and the front slide 1 are used for the guiding of the tool-stock exclusively.

What we claim as new and desire to secure by Letters Patent of the United States is:— 55

In a lathe bed front and back slides, gibs on said slides to guide the saddle or carriage, the front slide being arranged lower than the back slide and the gib of the front slide being arranged at approximately the same 60 level as the back slide for the purpose of obtaining a corresponding increase in the thickness of material counted in a vertical direction at the fore end of the saddle or carriage. 65

In witness whereof we have hereunto set our hands in the presence of two witnesses.

KARL OLSSON.

ANDERS HILMER OLSSON.
